The ornamental design for a top loading video cassette recorder, as shown and described.

DESCRIPTION

FIG. 1 is a top, front and right side perspective view of a top loading video cassette recorder showing my new design;

FIG. 2 is a top plan view thereof;

FIG. 3 is a front elevational view thereof;

FIG. 4 is an inverted left side elevational view thereof; FIG. 5 is a right side elevational view thereof, shown with the cassette load door open;

FIG. 6 is a rear elevational view thereof; and,

FIG. 7 is a bottom plan view thereof.

The broken line showings of the control buttons in FIGS. 1 and 3 and the jacks in FIG. 6 are for illustrative purposes only and form no part of the claimed design.
